UNITED STATES PATENT OFFICE.

ALVA D. LEE, OF BOSTON, MASSACHUSETTS, ASSIGNOR TO LEE FURNACE AND BURNER COMPANY, A CORPORATION OF NEW YORK.

POWDERED-COAL BURNER.

988,271.

Specification of Letters Patent. Patented Mar. 28, 1911.

Application filed July 1, 1909. Serial No. 505,769.

To all whom it may concern:

Be it known that I, ALVA D. LEE, a citizen of the United States of America, and a resident of Boston, in the county of Suffolk and 5 State of Massachusetts, have invented certain new and useful Improvements in Powdered-Coal Burners, of which the following is a specification.

This invention relates to an apparatus for 10 burning powdered coal or other fuel and has for its object the production of a device whereby the coal may be constantly fed through an opening in the furnace wall and mixed with the proper amount of air and 15 steam for combustion, the amount of coal fed through the device being suitably controlled while means is also provided for controlling the amount of air admitted to the furnace for the purposes of combustion.

20 The invention further consists in providing a means whereby the opening through the furnace may be hermetically sealed and thus limit the air admitted to the fire-pot to that which passes through the burner.

25 The invention further consists in certain novel features of construction and arrangement of parts which will be readily understood by reference to the description of the drawings and to the claims hereinafter 30 given.

Of the drawings: Figure 1 represents a vertical section of an apparatus embodying the features of this invention. Fig. 2 represents a section of the same, the cutting 35 plane being on line 2—2 on Fig. 1. Fig. 3 represents a vertical section, the cutting plane being on line 3—3 on Fig. 1. Fig. 4 represents a section, the cutting plane being on line 4—4 on Fig. 1. Fig. 5 represents a section of the aspirator and its 40 supporting plate, the burner being removed therefrom, the cutting plane being on line 5—5 on Fig. 2. Figs. 6 and 7 represent, respectively, an end and side elevation of 45 the annular boss secured to the wall plate. Fig. 8 represents in section the cam faces of the annular boss and the hub of the damper, and Fig. 9 represents a section through the damper hub on line 9—9 on Fig. 2.

50 Similar characters designate like parts throughout the several figures of the drawings.

In the drawings, 10 represents the wall of a furnace through which extends the opening 55 11 into the fire-pot. To the front face

of the wall 10 is secured in any well-known manner a perforated annular plate 12 to the central portion of which is secured the threaded annular boss 13. Screwed into the threaded opening of the boss 13 is the tubular casing member 14 to which air may be admitted through the pipe 15. Threaded to the interior of the casing member 14 is the tubular member 16 having openings 17 therein in the same plane with the inlet pipe 18 through which steam may be admitted to the interior of the tubular member 16. Threaded to the interior of the member 16 is the tubular member 19 to the outer end of which is secured a head 20 which communicates with a feed hopper 21 adapted to receive the powdered coal or other fuel intended to be used in the burner. The hopper 21 is provided with a feed screw 22 to the upper end of which is secured a gear 23 meshing with a gear 24 on the shaft 25 driven by means of a belt 26 from a suitable electric motor 27, the speed of which is controlled by means of the rheostat 28 of any well-known construction. It is obvious that by 60 means of this rheostat the speed of the motor 27 may be regulated as desired and as a consequence the feed of the pulverized coal or other fuel from the hopper 21 into the interior of the tubular member 19 may be 65 controlled at will.

Beneath the discharge end of the hopper 21 is located an air pipe 29 having therein a regulating valve 30. The inner end of the pipe 29 is reduced in diameter to form a 70 jet 31 through which the air passes into the interior of the tubular member 19 with such force as to create a blow pipe action therein, thus causing the pulverized coal or fuel fed therein from the hopper 21 to be forced 75 through the interior of the tubular member 19 and discharged from its opposite end 32. The tubular members 16 and casing 14 are reduced in diameter at their forward ends 80 immediately in front of the discharge end 32 so that the steam and air within said tubular members in passing from the outlet ends of said members will pass across the path of the discharge of the pulverized coal or other fuel and be thoroughly mixed therewith in the mixing chamber 33 of the member 34, screwed onto the periphery of the 85 casing member 14.

Surrounding the member 34 is an aspirator 35 supported by means of the legs 36 se- 90

cured to the inner face of the plate 12. The outer face of the plate 12 has mounted in a recess therein and surrounding the perforations therethrough a sheet of packing material 37 against which the perforated damper member 38 bears. This damper member 38 is provided with perforations therethrough adapted to register with the perforations through the plate 12. The hub 5 of the damper member 38 is mounted upon the boss 13 and is freely revoluble about the same, being held in position by means of the flange 39 formed upon said boss 13. The hub of the damper member 38 is provided 10 with a plurality of cam members 40 on its outer face which are adapted to engage with similar cam members 41 formed upon the inner wall of the flange 39 of the boss member 13. It is obvious that this damper member 38 bearing as it does against the packing material 37 when turned about its axis will be pressed into the packing material by the action of the cam members 40—41 acting upon each other. The cam members 40 and 41 are so located relative to each other that they will coöperate to force the damper of the packing material 37 only 15 when the perforations in the damper are out of register with the perforations in the plate 12. It is obvious therefore that when the damper is moved about the axis of the burner by means of the handle 42 to close the opening through the furnace wall into the fire-pot that the cam action of these members 40 and 20 41 will press the damper so firmly into contact with the packing material as to hermetically seal the opening and prevent any air from passing therethrough. The damper may be moved into any position to permit 25 the admission of a greater or lesser amount of air through the opening 11 and locked in adjusted position by means of the threaded clamp 43.

The device provides a means whereby powdered coal or similar fuel may be automatically forced into the fire-pot of a furnace under a greater or less degree of pressure and thoroughly mixed at its discharge from 30 said device with any required amount of steam and air for combustion in a vacuum or a greater amount of air may be admitted under atmospheric pressure through a suitable aspirator and caused to mix with the fuel and steam and air being discharged from the main portion of the burner.

It is obvious that by means of the handle 44 the amount of air being discharged from the tubular casing member 14 may be controlled while by means of the handle 45 in 35 like manner the amount of steam being discharged from the tubular member 16 may be similarly regulated.

This apparatus provides a very effective means of utilizing powdered fuel and controlling the feed of the fuel and the dis-

charge of the fuel to the fire-pot under varying conditions while at the same time it provides a ready means of controlling the amount of air or steam to be mixed with the powdered coal or fuel as it is discharged 70 from the discharge orifice 32. It also provides a ready means of cutting off and hermetically sealing the opening through the furnace wall or regulating the amount of opening therein through which the air may 75 pass through the aspirator 35 into the fire-pot, thus providing for every contingency which may arise under varying conditions in the operation of the burner.

By removing the nozzle member 34, the 80 effect upon the powdered coal passing from the mouth 32 of the member 19 by the impact thereon at a given point of the steam and compressed air passing from the mouths of the members 16 and 14 is to cause it to be 85 scattered and spread, getting an effect known as "ballooning." It is obvious that as the steam passes through the member 16 at a high rate of speed and concentrates at a common point it will distribute the powdered 90 coal in every direction throughout the fire-pot and prevent it from entering said fire-pot in a jet flame. The distribution of the powdered coal throughout the fire-pot produces an equalized flame with a great increase in effectiveness over any result that 95 can be obtained by introducing the coal into the fire-pot in a jet as is now generally done. While the best results may be obtained in "ballooning" by removing the head member 100 34, it is obvious that fairly good results may be obtained without the removal of this member, the spread of the coal, however, being more limited.

It is believed that the operation and many 105 advantages of the apparatus thus described will be fully apparent without any further description.

Having thus described my invention, I 110 claim:

1. A powdered fuel burner of the nature disclosed combining a central tube for projecting powdered fuel, a power driven mechanical feeder for supplying said tube with powdered fuel, an adjuster for longitudinally shifting said tube, an intermediate pipe circumscribing said tube and converging at its extremity to form an annular steam passage adapted to project a converging 115 jet of steam into the projected stream of powdered fuel, an adjuster for longitudinally shifting said pipe, means for supplying the same with steam, an outer tubular member circumscribing said pipe and converging at 120 its extremity to form an annular air passage adapted to project a converging jet of air into the stream of commingled fuel and steam, means for supplying said tubular member with air, a tip having a bell-shaped recess for diffusing and discharging the fuel, 125 130

steam and air, an aspirator arranged adjacent said tip for supplying additional air, and adjustable means for regulating the action of said aspirator.

5 2. A powdered fuel burner of the nature disclosed combining a central tube for projecting powdered fuel, a feeder for supplying said tube with powdered fuel, an adjuster for longitudinally shifting said tube 10 to vary the proportions of steam in the combustible mixture, an intermediate pipe circumscribing said tube and converging at its extremity to form an annular steam passage adapted to project a converging jet of steam 15 into the projected stream of powdered fuel, means for supplying the same with steam, an adjuster for longitudinally shifting said pipe to vary the proportions of air in the combustible mixture, an outer tubular member 20 circumscribing said pipe and converging at its extremity to form an annular air passage adapted to project a converging jet of air 25 into the stream of commingled fuel and steam, means for supplying said tubular member with air; a tip having a bell-shaped recess for diffusing and discharging the combustible mixture, an aspirator arranged adjacent said tip for supplying additional air, and adjustable means for regulating the action of said aspirator.

3. A powdered fuel burner of the nature disclosed combining a central tube for projecting powdered fuel, a power-driven mechanical feeder for supplying said tube with powdered fuel, an air pipe coöperating with said feeder for forcing the fuel in disseminated form through said tube, an adjuster for longitudinally shifting said tube, an intermediate pipe circumscribing said tube 40 and converging at its extremity to form an annular steam passage adapted to project a converging jet of steam into the projected stream of powdered fuel, means for supplying the same with steam, an adjuster for longitudinally shifting said pipe, an outer tubular member circumscribing said pipe and converging at its extremity to form an annular air passage adapted to project a converging jet of air into the stream of commingled fuel and steam, means for supplying said tubular member with air, a tip having a bell-shaped recess for diffusing and discharging the combustible mixture, an aspirator arranged adjacent said tip for supplying additional air, and adjustable means for regulating the action of said aspirator.

4. A powdered fuel burner of the nature disclosed combining a central tube for projecting powdered fuel, a feeder for blowing powdered fuel through said tube, an adjuster for longitudinally shifting said tube, an intermediate pipe circumscribing said tube and converging at its extremity to form an annular steam passage adapted to project a converging jet of steam into the projected

stream of powdered fuel, said pipe having a peripheral shoulder and being provided with a perforation rearward of said shoulder whereby steam may pass therethrough into the bore of said pipe, an adjuster for longitudinally shifting said pipe, an outer tubular member circumscribing said pipe and converging at its extremity to form an annular air passage adapted to project a converging jet of air into the stream of commingled fuel and steam, means for supplying said tubular member with air, said outer tubular member having an internal fluid-tight fit with the peripheral shoulder on said intermediate pipe and having a steam inlet 70 at the rear of said shoulder, a tip having a bell-shaped recess for diffusing and discharging the fuel, steam and air, an aspirator arranged adjacent said tip for supplying additional air, and adjustable means for 75 regulating the action of said aspirator.

5. A powdered fuel burner of the nature disclosed combining a central tube for projecting powdered fuel, a feeder for blowing powdered fuel through said tube, an adjuster for longitudinally shifting said tube, an intermediate pipe circumscribing said tube and converging at its extremity to form an annular steam passage adapted to project a converging jet of steam into the projected 90 stream of powdered fuel, an adjuster for longitudinally shifting said pipe, means for supplying the latter with steam, an outer tubular member circumscribing said pipe and converging at its extremity to form an annular air passage adapted to project a converging jet of air into the stream of commingled fuel and steam, means for supplying said tubular member with air, a tip having a bell-shaped recess for diffusing and discharging the combustible mixture, an aspirator arranged adjacent said tip for supplying additional air, and a damper for regulating the flow of air into said aspirator.

6. A powdered fuel burner of the nature disclosed combining a central tube for projecting powdered fuel, a power-driven mechanical feeder for supplying said tube with powdered fuel, an air pipe coöperating with said feeder for forcing the fuel in disseminated form through said tube, an adjuster for longitudinally shifting said tube to vary the proportions of steam in the combustible mixture, an intermediate pipe circumscribing said tube and converging at its extremity to form an annular steam passage adapted to project a converging jet of steam into the projected stream of powdered fuel, said pipe having a peripheral shoulder and being provided with an inlet to its interior rearward of said shoulder whereby steam may pass therethrough into the bore of said pipe, an adjuster for longitudinally shifting said pipe to vary the proportions of air in the combustible mixture, means for supplying 105 110 115 120 125 130

the pipe with steam, an outer tubular member circumscribing said pipe and converging at its extremity to form an annular air passage adapted to project a converging jet 5 of air into the stream of commingled fuel and steam, means for supplying said tubular member with air, said outer tubular member having an internal fluid-tight fit with the peripheral shoulder on said intermediate 10 pipe and having a steam inlet at the rear of said shoulder, a tip having a bell-shaped

recess for diffusing and discharging the combustible mixture, an aspirator arranged adjacent said tip for supplying additional air, and a damper for regulating the flow of air 15 into said aspirator.

Signed by me at 4 Post Office Sq., Boston, Mass., this 24th day of December, 1908.

ALVA D. LEE.
